United States Patent Office.

JOSEPH A. RUFF, OF SOMERVILLE, MASSACHUSETTS, ASSIGNOR TO THE RUSSELL & ERWIN MANUFACTURING COMPANY, OF NEW BRITAIN, CONNECTICUT.

Design No. 3,823, dated January 25, 1870.

DESIGN FOR DOOR-ESCUTCHEON.

The Schedule referred to in these Letters Patent and making part of the same

I, JOSEPH A. RUFF, of Somerville, in the county of Middlesex, and State of Massachusetts, have invented and produced a new and original Design for a Door-Escutcheon, of which the following is a specification.

A combination of curved and straight lines forms the outlines of the design for door-escutcheon into the various points and angles, as shown in the accompanying photograph.

A raised moulding, *a*, borders the design.

Immediately below the key-hole is a star, *b*, enclosed by a circular band.

The remaining portion of the finely-matted ground is covered by raised ornamental scroll-work.

Surmounting the knob-escutcheon *A* is a cap, *B*, ornamented in harmony with the rest of the design.

I claim, as my invention—

The ornamental design for a door-escutcheon, substantially as described and shown.

JOSEPH A. RUFF.
